UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

LASTING-MACHINE.

1,399,892.

Specification of Letters Patent. Patented Dec. 13, 1921.

Application filed January 17, 1919. Serial No. 271,642.

To all whom it may concern:

Be it known that I, THOMAS H. SEELY, a citizen of the United States, residing at Malden, in the county of Middlesex and 5 State of Massachusetts, have invented certain Improvements in Lasting-Machines, of which the following description, in connection with the accompanying drawings, is a specification, like reference characters on the 10 drawings indicating like parts in the several figures.

This invention relates to lasting machines of the class employing a gripper for pulling an upper and laying it over a last and preferably provided with means such as a wiper to press the upper into lasted position to be secured at the toe by tracks. The invention is illustrated as applied to a machine of the general type shown in United States Letters 15 20 Patent No. 584,744, granted June 15, 1897 upon the application of Ladd and McFeely, and has for one object to provide improved gripper operating mechanism adapted for use in machines of this type. At the toe and 25 sometimes at other parts of the shoe the gripper is required to plait or fold the marginal portion of the upper upon the shoe bottom to take care of the fullness which is incident to bending the upper inwardly 30 over the convex edge of the last bottom.

In machines of prior construction such as that of the patent referred to above the plaiting movements of the gripper comprise a lateral movement and a twisting movement, these movements being so related that when the lateral movement is toward the right the twisting movement is toward the left or counter-clockwise and vice versa. While machines thus organized have been 35 used successfully in large numbers, it is recognized by those technically skilled in shoe making that this operation of the gripper of machines of prior construction does not strictly correspond to the operation effected by the hand workman with his pincers for the reason that the hand workman, while drawing the upper on the left side of a shoe toe, as seen from the bottom, toward the right, gives his pincers a twisting movement 40 in the same direction, toward the right, or clockwise, with the result that a plait or fold is formed in the upper between the pincer and the point last secured instead of being formed on the advance side or toward the

unlasted portion of the upper as is done by 55 the gripper of hand method lasting machines as previously organized. Conversely, when lasting the right side of the toe the hand workman moves his pincers toward the left and twists them in the same direction or 60 counter-clockwise.

An object of this invention is to provide a hand method lasting machine which, while retaining the many highly desirable and valuable features of prior machines of this 65 type, will embody novel mechanism for operating the gripper which will give it the same movements as those given to a hand pincer by a workman in the hand lasting 70 operation.

An important feature of the invention consists in a novel organization including a gripper having its shank arranged substantially perpendicular to the last bottom, means for imparting lateral movements to 75 the gripper, and means for imparting a twisting movement to the gripper which is in the same sense as the lateral movement, that is, when the lateral movement is toward the right the twisting movement of the 80 gripper will be toward the right or clockwise as viewed from above. Conversely, when the lateral movement is toward the left the twisting movement of the gripper will be toward the left or counter-clockwise. 85 This combination of movements of the gripper imitates accurately the action of the pincers as used by the hand laster and results in a better disposition of the stock than is possible in machines of the hand method 90 type as previously organized.

In lasting a shoe it is the usual practice to have the upper in pulled over condition with a single tack holding the upper at the end of the toe and a tack or tacks holding the upper at each side of the toe, the upper bulging away from the last on both sides of the toe between the points secured by the tacks. With the upper in this condition the upper is lasted in McKay work from the toe tack rearwardly, first on one side of the toe and then on the other side of the toe. In order to grasp the upper which bulges away from the last on each side of the toe tack, it is necessary to give the gripper a 100 preliminary position at one side or the other of the longitudinal median line of the toe and to turn the gripper so that the gripping

faces of the jaws will be in a position approximately parallel with the edge portion of upper to be gripped.

A further feature of the present invention 5 consists in an organization comprising means arranged to give the gripper preliminarily the proper lateral and axially turned position to grasp the upper on either side of the toe and power operated means for giving 10 the gripper a further axial turning movement in the same direction as that in which the gripper was turned in the preliminary setting of the gripper and for moving the gripper bodily inwardly of the shoe.

15 A further feature of the invention consists in means arranged for adjustment to vary the amount of angular or axial turning movement imparted to the gripper in the preliminary setting and preferably without 20 affecting the amount of lateral movement given to the gripper in the preliminary setting. In the construction shown herein, when adjustment is made to increase the manually effected turning movement, the 25 amount of turning movement effected by power is diminished and vice versa; the total amount of turning movement remaining substantially the same.

These and other features of the invention 30 will appear more fully from the following detailed description when read in connection with the accompanying drawings and will be pointed out in the appended claims.

In the drawings,—

35 Figure 1 is a side elevation of a hand method lasting machine embodying this invention;

Fig. 2 is a perspective view, partly in section, of the gripper operating mechanism;

40 Fig. 3 is a perspective detail of separated parts of the mechanism shown in Fig. 2;

Fig. 4 is a sectional view of parts shown in Fig. 2;

Fig. 5 is a front elevation of parts shown in 45 Fig. 2;

Fig. 6 is a diagrammatic view indicating the motion of parts shown in Fig. 5;

Fig. 7 is a view of the toe of a shoe showing in section the gripper in its preliminary position and grasping the upper; and

50 Fig. 8 is a similar view showing the gripper performing its power operated movements.

In the drawings, the numeral 2 indicates 55 the column of the machine upon which the head 4 is mounted, the head supporting many of the operating parts of the machine. On the head 4 is a rest 6 for giving support to the bottom of the last and a gage 8 has its end 60 face in position to support the edge or side of the last. A gage 9 may be moved rearwardly to expose the thin gage 8 for use at the sides and shank of the shoe, the edge gage mechanism, as well as the mechanism for supplying 65 and driving the tacks of different size em-

ployed in lasting, being, preferably, and as shown herein, similar to that disclosed and claimed in United States Letters Patent No. 999,233, granted August 1, 1911, upon application of Ladd and Stiggins. The shoe, having been prepared for lasting by assembling an innersole, upper, lining and counter upon a last and pulling over the upper at the toe and sides as usual and securing it to the innersole by a tack or tacks at each of these 75 places, is supported bottom upward against the rest 6 and laterally against the gage 8 in position to be operated upon. The main shaft 10 is operated by a driving pulley 12, the shaft supporting the various cams for 80 operating the several mechanisms including the gripper. Said gripper comprises jaws 14, 16 carried by shanks 13, 15 which are arranged substantially perpendicular to the last bottom and are so connected as to permit 85 independent relative longitudinal movement for opening or closing the gripper but which are moved together for imparting the usual movements to the gripper, as will be explained. The gripper is mounted in the front 90 end of a lever 18 which is pivoted at 20 and connected at its rear ends through a spring 22 to a plate 24 operated by a groove in a cam block 26 by which the lever is rocked to raise 95 and lower the gripper to give it what is known in the art as its updrawing movement to tension the upper. One jaw of the gripper is operated relatively to the other by means of a cam 28 acting to depress an arm 29 which actuates the shank 15 of the movable gripper 100 jaw in the usual manner in machines of this type. Overdraw movement is imparted to the gripper by a rod 30 connected to the gripper at its forward end and impelled forwardly by a spring lever 32 engaging its rear 105 end, the movement of the overdraw rod being controlled by a cam 34 engaging a cam roll 36 mounted on the rod.

A combined wiper and tack carrier 21 is mounted on a longitudinally movable bar 23 110 which is reciprocated by a lever 25 operated by a cam 27 on the shaft 10. Tacks are delivered to the tack carrier 21 from a double raceway 29 by a separating and feeding device 31. The raceway is provided with two 115 channels for supplying different kinds of fastenings, for example, different lengths of tacks, the longer tacks being used at the toe and heel in McKay work and the shorter tacks at the sides and shank.

The grippers are moved laterally from side to side of their central position by a rock shaft 40 having fixed thereon a pinion 42 engaged by a segment rack on a lever 46 which is actuated to rock the shaft 40 by a 125 connection with a cam path in the front face of the cam block 26. The front end of the shaft 40 is provided with a segment block or rocker 48. The shaft 40 is tubular and a shaft 50 is contained therein (Figs. 2 and 4). 130

Splined on the shaft 40 is a sleeve 42 having a spiral slot 54 into which projects a pin 56 fixed in the shaft 50 by a set screw 58. The shaft 40 is slotted at a right angle to its axis 5 to permit movement of the pin 56 when the shaft 50 is rotated. The sleeve 52 is grooved at 60 to receive rolls on the arms of a yoke 62 which yoke forms one arm of an angle lever pivoted at 64, the other arm 66 being 10 bifurcated and pivoted to an operating rod 68. The rod 68 is guided at its lower end through a bracket 70 on the machine frame and has clamped thereto a block 72 carrying a roll 74 arranged to engage an inclined slot 15 in a block 76 formed on the end of a knee lever 78. The knee lever is pivoted at 80 to the machine frame and is operated by a knee yoke 82 to cause the rod 68 to be moved up and down and to cause the sleeve 52 to be 20 moved longitudinally on the shaft 40. This movement causes rotation of the shaft 50 relatively to the shaft 40 because of the action of the spiral slot 54 upon the pin 56. The shaft 50 is provided at its front end with 25 a pinion 84 which engages teeth 86 formed on a sliding plate 88 which is held in place on the block 48 by studs 90 which pass through slots in the block 48 and are held in place by screws 92 and washers 94, as 30 shown in Fig. 5. On the plate 88 is a bearing stud 96 carrying a sleeve 98 to which is secured by cone bearing screws 100 a yoke 102 which is connected to the gripper by the usual mechanism for yieldingly imparting 35 thereto its lateral movements. It will be seen that, by movement of the knee lever 78, the position of the bearing stud 96 relatively to the axis of oscillation of the rocker 48 may be controlled and positioned either above or 40 below said axis of oscillation or located in line with that axis so that no lateral movement will be imparted to the gripper. When the stud 96 is in this central or neutral position, the gripper is located in the longitudinal cross-sectional plane of the machine 45 and centrally of the toe of the shoe presented to the machine. Since the toes of shoes prepared for lasting have a pulling over tack at the end of the toe, it is necessary, before beginning 50 the lasting operation, to locate the gripper at one side of this central cross-sectional plane or, speaking with reference to the shoe, at one side of the longitudinal median line of the shoe, such position of the 55 gripper being indicated in Fig. 7.

The machine is preferably arranged, as herein shown, to be stopped at a predetermined point in the cycle at which point the grippers are opened and the rocker 48 is in the position shown in Fig. 5. Suitable stop mechanism for this purpose is disclosed in Letters Patent of the United States, No. 1,356,406, granted October 19, 1920, on my application. When the machine is stopped 60 in this position, movement of the knee lever 65

to cause the slide 88 to move upwardly will effect a preliminary lateral movement of the gripper toward the right hand side of the toe, as shown in Fig. 7, and if the slide 88 is moved downward below said position, the 70 gripper will, of course, be positioned on the opposite or left hand side of the shoe. In either case the gripper will be laterally positioned to seize the outwardly bulging portion of the upper on each side of the pulling 75 over tack at the toe.

However, since the edge of the upper at neither side of the toe extends in a plane perpendicular to the longitudinal median line of the shoe, it is necessary to turn the gripper 80 so that the gripping faces of the jaws will be substantially parallel with the portion of upper to be gripped. This also will be obvious from Fig. 7.

The preliminary turning movement of the 85 gripper in position to grip the stock and the further turning movement of the gripper under power operation, are effected by mechanism which will now be described. The stud 96 has a forwardly extending reduced 90 portion 110 upon which is pivoted a block 112, as best shown in Fig. 3. The block 112 engages a slot 114 formed in a block 116 which has a cylindrical stem 117 adjustably held in a split clamp formed in the end of 95 one arm 118 of an angle lever pivoted at 120 to the machine frame. The stem 117 is held clamped in the end of the lever by tightening a clamp screw 119. The other arm 122 of the angle lever extends substantially vertically (Fig. 2) and has in its upper end a slot 124 in which is adjustably held a roll stud 126 by a nut 128. A roll 130 upon the stud 126 engages a slot in the lower end of a lever 132 fulcrumed at 134 on a rigid 100 strut 136 secured to the machine frame. Between its ends the lever 132 is connected by a ball joint 138 to one end of a connecting rod 140. The other end of the connecting rod is pivoted at 142 to a slide 144 having on 105 its front face teeth 146 which engage teeth formed in a ball 139 by which the gripper shank 13 is supported, the construction being such that when the slide 144 is moved longitudinally, the gripper will be turned 110 about the longitudinal axis of its shank portion 13.

It will now be clear that upward movement of the arm 118 will swing the arm 122 to the left (Fig. 2) and cause a corresponding movement of the slide 144 to twist or turn the gripper in a counter-clockwise direction. Such a movement is effected by operating the knee lever to move the slide 88 upwardly beyond its neutral position by reason of the action of the block 112 in the slot 114 of the block 116 fixed to the end of the arm 118, the amount of movement being determined by the angular relation of the slot 114 to the direction of upward sliding move- 115 120 125 130

ment of the slide 88, the block 48 on which the slide 88 moves being assumed to be in the position shown in Fig. 4 which is the position it assumes when the machine is stopped.

5 The amount of this preliminary turning movement of the gripper may be varied by changing the angular relation of the slot 114 in the block 116 relatively to the direction of movement of the slide 88 which may be 10 done by loosening the screw 119 and turning the stud 117 in the end of the arm 118. For this purpose the outer end of the stud 117 is provided with a slot 115 which preferably extends in the same direction as the 15 slot 114 and in which an implement may be inserted to turn the block 116. The slot 115, being readily seen by the operator, indicates to him the setting of the slot 114. If the slot 114 is arranged parallel with the direction 20 of movement of the slide 88, movement of the slide will, of course, impart substantially no turning movement to the gripper, and if the slot is arranged at right angles to the direction of movement of the slide, the 25 greatest amount of angular turning movement will be imparted to the gripper by the preliminary upward movement of the slide, while the power effected rocking motion of the block 48 would impart substantially no 30 turning movement to the pincers. The setting of the block 116 is preferably such that, during the preliminary setting of the slide to move the gripper laterally, it will be given 35 a sufficient turning movement to enable it properly to grasp the outwardly bulging upper at the side of the toe, as indicated for instance in Fig. 7.

The operation of the mechanism above 40 described will perhaps be made clearer by the diagram of Fig. 6 in which the line marked 48 indicates the position of the rocker 48 before the machine is started and the dotted line 48^a the position to which it is rocked during each cycle of the machine. 45 120 indicates the pivot of the angle lever 118, 122, and 117 the initial position of the center of the block 116 carried by the arm 118, succeeding positions being indicated by 117^a and 117^b. The center of the stud 110 on the 50 slide 88 initially coincides with the center 117 and its successive positions are indicated by 110^a and 110^b. When the slide 88 is moved upwardly manually by the knee lever, 55 the stud 110 assumes the position 110^a and the center 117, the position 117^a, causing the arm 118 to be moved to 118^a through the angle indicated. This, of course, causes a counter-clockwise turning movement of the 60 gripper and a lateral positioning movement toward the right. When the rocker 48 is moved by power to the position 48^a, the stud 110 is moved to the position 110^b, the center 117 caused to assume the position 117^b, and 65 the arm 118 moved through the angle in-

dicated to the position 118^b. This causes a further turning movement of the gripper in the same direction as before and moves the gripper laterally toward the left.

If, on the other hand, the machine is to 70 operate upon the upper at the left hand side of the toe, the angle lever will be operated to move the slide 88 downwardly, causing the gripper to be moved laterally toward the left and consequently giving it a preliminary turning movement toward the right 75 or clockwise. This positions the gripper for operating on the upper at the left side of the toe. When the machine is started the lower end of the block 48 will, of course, move to the right, causing the gripper to move toward the right or toward the longitudinal median line of the shoe and at the same time causing further turning movement 80 of the gripper toward the right or clockwise. The amount of turning movement imparted to the gripper by the rocker in a given position of the slide 88 is determined by changing the location of the roll stud 126 in the slot 124. 85

90 It will be understood, of course, that, after giving the gripper its proper preliminary position on one side of the toe for the first operation of the gripper to last the upper, the operation may be continued, without 95 stopping the machine, to last successively portions of the upper along the side of the toe, and that during this operation the knee lever may be manipulated to vary the lateral and turning movements of the gripper, as 100 the condition of the stock demands. 90

Referring to Figs. 7 and 8, Fig. 7 indicates the position the gripper has been made to assume by the preliminary movement of the knee lever to move the slide 88 upwardly 105 and position the gripper laterally toward the right for turning it toward the left or counter-clockwise into position to seize the upper. Fig. 8 shows the action of the gripper after the machine starts, the gripper having turned further toward the left or counter-clockwise, so as to form a plait between the gripper and the toe tack. In the subsequent operations of the gripper, the plait will also be formed on that side of the 110 gripper which is toward the toe. In operating upon the other side of the toe, the action will be reversed, the gripper being given a preliminary position to the left of the longitudinal median line of the shoe and turned 115 in a clockwise direction preliminarily and being operated by power to move to the right toward the longitudinal median line of the shoe and turned further in a clockwise direction 120 thereby forming a plait on the side of the gripper toward the toe. It will be understood, of course, that the gripper is given updraw and overdraw movements in addition to the lateral and turning movements, 125 and that the upper is wiped down upon the 130

innersole and secured by tacks, as is usual in the type of lasting machine herein set forth.

Having thus described my invention, what I claim as new and desire to secure by Letters 5 Patent of the United States is:

1. In a machine of the class described, the combination of a gripper having its shank disposed substantially perpendicular to the shoe bottom, means for operating the gripper

10 to seize the stock, means for effecting up-draw and overdraw movements of the gripper, means for giving the gripper a lateral movement, after it grips the stock, inwardly of the shoe, and means for giving 15 the gripper a turning movement in a similar direction.

2. In a machine of the class described, the combination of a gripper having its shank disposed substantially perpendicular to the 20 shoe bottom, means for operating the gripper to seize the stock, means for effecting up-draw and overdraw movements of the gripper, means for giving the gripper a lateral movement toward the right, and means 25 for giving the gripper simultaneously a turning movement toward the right or clockwise.

3. In a machine of the class described, the combination of a gripper having its shank 30 disposed substantially perpendicular to the shoe bottom, means for operating the gripper to seize the stock, means for effecting up-draw and overdraw movements of the gripper, means for giving the gripper a lateral movement toward the right, means for giving the gripper simultaneously a turning 35 movement toward the right or clockwise, and means under the control of the operator constructed and arranged to cause both movements to be reversed.

4. In a machine of the class described, the combination of a gripper having its shank disposed substantially perpendicular to the shoe bottom, a rocker for effecting lateral 45 movement of the gripper after it grips the stock, and connections between the rocker and the gripper for giving the gripper a movement corresponding in direction of rotation to said lateral movement.

5. In a machine of the class described, the combination of an upper tensioning gripper arranged with its shank substantially perpendicular to the shoe bottom, means under the control of the operator for imparting to 55 the gripper lateral upper tensioning movements either to the right or left toward a central position, and means for imparting a turning movement to the gripper which is toward the right or clockwise when the lateral movement is toward the right and toward the left or counter-clockwise when the lateral movement is toward the left.

6. A lasting machine having, in combination, a gripper adapted to seize a portion of 65 the upper, means for operating the gripper

to work the upper over the shoe bottom, manually operable means to position the gripper preliminarily at one side of the central cross-sectional plane of the machine and to turn the gripper at an angle to said plane, 70 and power means for effecting a further angular movement of the gripper in the same direction to plait the upper and for moving the gripper toward said plane.

7. A lasting machine having, in combination, a gripper adapted to seize a portion of the upper, means for operating the gripper to work the upper over the shoe bottom, manually operable means to position the gripper preliminarily at one side of the central cross-sectional plane of the machine and to turn the gripper at an angle to said plane which angle may be varied without effecting lateral movement, and power means for effecting a further angular movement of the gripper in the same direction to plait the upper and for moving the gripper toward said plane.

8. A lasting machine having, in combination, a gripper adapted to seize a portion of the upper, means for operating the gripper to work the upper over the shoe bottom, manually operable means to position the gripper preliminarily at one side of a shoe toe and to turn the gripper at an angle to seize the edge of the upper bulging outwardly between the pulling over tacks, and power means for continuing said turning of the gripper and moving the gripper toward the longitudinal median line of the shoe 100 bottom.

9. A lasting machine having, in combination, a gripper adapted to seize a portion of the upper, means for operating the gripper to work the upper over the shoe bottom, manually operable means to position the gripper preliminarily at one side of the central cross-sectional plane of the machine and to turn the gripper at an angle to said plane, means constructed and arranged for adjustment to vary the preliminarily turning movement of the gripper while maintaining the amount of lateral movement of the same, power means for effecting a further turning movement of the gripper to 110 plait the upper in the same direction as the preliminary turning movement, and means to effect a lateral movement of the gripper inwardly of the shoe to lay the plaited upper over the shoe bottom.

10. A lasting machine having, in combination, a gripper adapted to seize a portion of the upper at the side of a shoe toe, means for operating the gripper to work the upper over the shoe bottom, said gripper being arranged to have a predetermined amount of turning movement in either direction from a central position, means adapted for operation for causing a predetermined portion of said turning movement to take place before 125 130

the stock is gripped, and power means for continuing said turning movement of the gripper during the movement of the gripper over the shoe bottom.

5 11. In a machine for lasting shoe toes, an upper tensioning gripper arranged to be operated to tension the upper over the last, means operable manually to position the gripper at one side of the longitudinal me-

10 dian line of the toe, and power operated means for moving the gripper toward said median line and for turning the gripper in the same direction as that in which the power effected lateral movement takes place.

15 12. In a machine for lasting shoe toes, an upper tensioning gripper arranged to be operated to tension the upper over the last, manually operable means to move the gripper laterally of the shoe toe toward the right

20 to position it for seizing the stock, and means operating under power actuation of the machine to move the gripper laterally toward the left and to turn the gripper counter-clockwise to plait the upper.

25 13. In a machine for lasting shoe toes, an upper tensioning gripper arranged to be operated to tension the upper over the last, means operable manually to move the gripper laterally of the shoe toe toward the left

30 to position it for seizing the stock, and means operating under power actuation of the machine to turn the gripper toward the right or clockwise to plait the upper.

14. In a machine for lasting shoe toes, an upper tensioning gripper arranged to be operated to tension the upper over the last, means arranged for adjustment to permit manual location of the gripper at one side of the longitudinal median line of the shoe toe

40 without affecting the angular position, and power means for moving the gripper toward said longitudinal median line and for turning the gripper to plait the upper.

15. In a machine for lasting shoe toes, an upper tensioning gripper arranged to be operated to tension the upper over the last, means arranged for adjustment to permit manual location of the gripper at one side of

the longitudinal median line of the shoe toe without affecting the angular position, and power means for moving the gripper toward said longitudinal median line and for turning the gripper in the same direction as the power effected lateral movement to plait the upper.

55 16. In a machine for lasting shoe toes, an upper tensioning gripper arranged to be operated to tension the upper over the last, means arranged for adjustment to permit manual location of the gripper at one side of the longitudinal median line of the shoe toe and for giving the gripper substantially its full turning movement to cause it to seize a portion of upper disposed at a wide angle to the last edge, and power means for moving the gripper toward the median line of the shoe toe without substantial turning movement.

60 17. In a machine for lasting shoe toes, an upper tensioning gripper arranged to be operated to tension the upper over the last, means for initially positioning the gripper at one side or the other of the longitudinal median line of the shoe toe and for setting the gripper angularly to receive the margin of the shoe upper, and power means for operating the gripper to work the stock over the shoe bottom including means for moving the gripper toward said longitudinal median line and turning the gripper in the same direction in which it was turned in setting it to receive the stock.

65 18. In a machine for lasting the toe of a pulled over shoe having a tack in the center of the toe, the combination of a gripper for seizing and tensioning the stock over the shoe bottom, a single means for setting the gripper laterally of the toe at one side of the tack and turning the gripper to seize the upper, and means for turning the gripper farther in the direction of its setting movement to form a plait in the upper between the gripper and the tack.

70 In testimony whereof I have signed my name to this specification.

THOMAS H. SEELY.
